EQUIPMENT FOR A PITCHING GAME
Thomas W. Lewis, 1204R Pattie Ave., Wichita, Kans.
Filed May 16, 1958, Ser. No. 735,853
2 Claims. (Cl. 273—100)

This invention relates to a pitching game. The object of the game is to pitch an element toward a scoring standard having supports thereon to receive the pitched element and the position of the pitched elements on or around the standard designates certain points of score.

The pitching elements are formed somewhat in the formation of a mule shoe, therefore the game is designated as "Mule Shoes."

These and other objects of the game will be more fully explained as this description progresses.

Now referring to the accompanying drawings, in which similar numerals of reference designate the same parts throughout the several figures of the drawings—

FIG. 1 is a front view of the scoring standard.

FIG. 2 is a side view of the scoring standard, shown in FIG. 1.

FIG. 3 is a side view of the scoring standard, shown in FIGS. 1 and 2.

FIG. 4 is a cross sectional view through the standard, the view being as seen from the line VI—VI in FIG. 1 and looking in the direction of the arrows.

FIG. 5 is a front detail view of the mule-shoe or pitching element, both sides being alike in construction.

FIG. 6 is a side view of the mule shoe shown in FIG. 5.

FIG. 7 is a front view of a modified form of the pitching standard, parts of which are broken away for convenience of illustration.

FIG. 8 is a top plan view of the device shown in FIG. 7.

FIG. 9 is an enlarged detail view illustrating some of the component parts of the scoring standard and their attachments, each to the other.

In the drawings the scoring standard is shown as being made of a single solid $\frac{1}{2}$ " round rod which has been heated at a central point and then folded against itself so that the flat sides of the rod abut each other to form a round standard S formed of the two halves 10 and 11, the upper ends of which have been bent and curved outwardly to form oppositely extending and upwardly directed curved or hook elements 12 and 13.

When the shaft is bent at the extreme lower end, the end forms a sharp point at 14 and the legs 10 and 11 immediately above the point 14 slope outwardly and in opposite directions from each other as indicated at 10a and 11a, then the portions above the sides 10a and 11a bend toward each other in a sloping position as illustrated at 10b and 11b from where they extend on upwardly in the manner above described to form the round standard S. The object of the formations 10a and 10b; 11a and 11b is to form an arrow head formation, which when pressed or driven into the ground will stabilize the standard S and prevent it from turning when the hooks 12 and 13 are struck by pitched mule shoes as will be readily understood.

The above described score pin device is designed for outdoor use and would be pressed or driven into the ground preparatory for playing the game.

The outfit for playing the game would include two

2

such scoring standards as above described that are spaced apart, preferably some thirty or forty feet or other desired distance, the standards being fixed in the ground as above described.

5 The pitching or mule shoe elements 15, as above mentioned, are mule shoe shaped and for purposes of balance, easy handling etc., are shaped alike on both sides, that, each end of the mule shoe has oppositely directed calks 16 and 16a; 17 and 17a and the front of the shoe has a toe calk which extends equally above and below the thickness of the shoe 15, as shown in FIG. 5. These mule shoes, for outdoor use, would probably be made of some substantial material such as iron, or aluminum, or the like, while for indoor use, the shoe might be made of rubber or plastic material, as desired.

In FIGURES 7, 8 and 9 is shown the indoor design of the equipment. In this design the device is provided with a heavy but portable base element 18 in the center of which is a square or rectangular depression or hole 19 that is designed to and does receive the lower end of the standard S which is fashioned to fit in the hole 19. In this instance the formations 10, 10a; 11 and 11a shown in FIG. 1 are omitted and the standard S shown in FIGS. 7, 8 and 9 is stabilized and prevented from turning by the lower end thereof being seated in the hole 19 in the base element 18 as above described.

20 In playing the game, the player would stand some prescribed distance, such as thirty, forty or fifty feet from the scoring pin and pitch the mule shoes to the pin in an effort to catch the mule shoe on one of the hooks 12 or 13 or catch the mule shoe around the top of the standard S, so that the shoe would rest partly in each of the hooks 12 and 13 or the shoe might rest on edge on the ground and lean against the standard S or the shoe might land on the ground and be positioned as a ringer around the standard S. Each of the positions would represent a specific score for the game.

25 The standard S' may be made of a single shaft of material such as wood, plastic, hard rubber or the like. The device is further provided with the hook elements 12a and 13a that are positioned one against the opposite sides of the upper end of the shaft S' and extend outwardly in opposite directions. The adjacent ends of the hooks 12a and 13a are folded against themselves as shown at 20 and 21 and positioned each against the other and the lower ends thereof resting on the upper end of the shaft S'. The hooks 12a and 13a are rigidly held in the position above described by means of a pair of rivets 22 and 23 that are passed through the material of the hooks 12a and 13a and the upper end of the standard S' to rigidly hold the several parts of the assembly together.

30 While the device as described is probably the preferred form of the device, it is to be understood that such modifications of the device may be employed as lie within the scope of the appended claims without departing from the spirit and intention of the invention.

35 Now having fully shown and described my invention, what I claim is:

40 1. A scoring standard for a pitching game; said standard being made of a single piece of solid, half round malleable material; said piece of material being bent at its mid-portion and folded together to form two legs with the flat surfaces on each side of the bend lying each against the other to form a round shaft, the upper end

portion of each leg being bent in an outward projecting hook-like formation; the lower end portion of each of said legs being bent outwardly to provide a diamond shape formation on the lower end of the scoring standard to prevent the standard from turning when the lower end of the scoring standard is positioned in the ground, the upper end portion of the said legs immediately preceding the hook formations providing a driving end by which the lower end of the standard may be driven into the ground.

2. A scoring standard for a pitching game as claimed

in claim 1, in combination with pitching elements; said pitching elements having an opening therein for receiving the hook elements on the standard and for receiving the standard within the curve of the pitching element, 5 for scoring purposes.
